US0D1011300S

(12) **United States Design Patent** (10) **Patent No.:** **US D1,011,300 S**
(45) **Date of Patent:** **** Jan. 16, 2024**

(54) **FUSE**

(71) Applicant: **Dexterials Corporation**, Shimotsuke (JP)

(72) Inventor: **Koichi Mukai**, Tochigi (JP)

(73) Assignee: **Dexterials Corporation**, Shimotsuke (JP)

(**) Term: **15 Years**

(21) Appl. No.: **29/792,033**

(22) Filed: **Feb. 28, 2022**

(30) **Foreign Application Priority Data**

Sep. 1, 2021 (JP) ..... 2021-018906 D

(51) **LOC (14) Cl.** **13-03**

(52) **U.S. Cl.**

USPC **D13/161**; D13/160

(58) **Field of Classification Search**

USPC D13/158, 160, 161, 182, 184, 199

CPC .. H01H 85/20; H01H 85/202; H01H 85/2015;

H01H 37/76; H01H 2085/0414; H01R

13/688; H01R 13/684

See application file for complete search history.

(57) **CLAIM**

The ornamental design for a fuse, as shown and described.

DESCRIPTION

FIG. 1 is a top perspective view of a fuse showing my new design;

FIG. 2 is a bottom perspective view thereof;

FIG. 3 is a front view thereof, the rear view being identical;

FIG. 4 is a right side thereof;

FIG. 5 is a left side view thereof;

FIG. 6 is a top view thereof;

FIG. 7 is a bottom view thereof;

FIG. 8 is a cross-section end view taken along line 8-8 in FIG. 3; and,

FIG. 9 is a cross-section end view taken along line 9-9 in FIG. 4.

The broken lines in the drawings depict portions of the fuse that form no part of the claimed design.

1 Claim, 9 Drawing Sheets
